END CONNECTOR

John W. W. Holden, Providence, R. I.

Application October 21, 1939, Serial No. 300,513

1 Claim. (Cl. 24—265)

My present invention relates to elastic ribbons equipped with end connectors and more particularly to the end connector construction.

The principal object of the present invention 5 is to provide an elastic ribbon having end connectors which can be readily applied or attached to a hat or similar article without sewing or without requirement of tools.

Another object of the present invention is to 10 provide an end connector which can be readily stamped from sheet stock and which can be easily attached to the end of the elastic ribbon.

A further object of the present invention is to 15 provide an end connector which can be firmly and permanently clamped to the end of an elastic ribbon without the use of special tools.

With the above and other objects and advantageous features in view, my invention consists 20 of a novel arrangement of parts more fully disclosed in the detailed description following, in conjunction with the accompanying drawing, and more specifically defined in the claim appended thereto.

In the drawing: 25 Fig. 1 is a perspective view of a lady's hat showing the attachment of the elastic ribbon and end connector of the present invention;

Fig. 2 is a plan view of the blank for forming the end connector;

Fig. 3 is a perspective view of the end connector ready for assembly with the elastic ribbon;

Fig. 4 is a perspective view of the end connector attached to the end of the elastic band and ready for assembly to the hat; and

Fig. 5 is a perspective view of the elastic band and end connector attached to the sweat band of a hat.

The ladies' hats made and sold recently are mainly of the type having small depth and different kinds of odd shapes and sizes, so that the hat perches on the top of the head. It is therefore desirable to attach an elastic strap or band which runs from the hat to the back of the head and thus holds the hat on the top of the head. Inasmuch as the hat is usually not equipped with the band when it is purchased from the store, it is necessary for the user to supply her own band if she wishes to thus equip the hat.

To this end, I have provided an elastic band 50 of any suitable material, as for example elastic tape, which may be attached to the hat 11 by means of end connectors 12 mounted on each end of the elastic band. The elastic band 10 may be of any desired shade and color so that

the purchaser can pick a color to match the hat, and the end connectors 12 are designed for quick securing to the inner side of the hat sweat band 13 so that the ends of the elastic band are not visible when the hat is worn.

The end connector 12 is formed from a blank 14, see Fig. 2, which is readily stamped from sheet stock, the blank being preferably in the form of a base plate generally rectangular in shape and provided with elongated prongs 15 10 extending from opposite side edges and serrations or teeth 16 on the lower edge. The end connector is then shaped by bending or folding the base plate longitudinally along the dotted lines 17, see Fig. 2, into the form shown in Fig. 15 3. This provides a generally flat rectangular lower plate portion 18 with the prongs 15 extending from either end thereof and having a turned up edge flange 19, and an integral upper plate portion 20 which is slightly smaller and is 20 provided with the serrations or teeth 16 which extend towards the base 18 and are adapted to seat within the flange 19.

The end connector is attached to the elastic band as shown in Fig. 4, the end of the elastic 25 band being placed between the plate portions 18 and 20 and the end connector being pressed together to force the serrations 16 through the elastic ribbon material and behind the upturned edge flange 19, as illustrated at 21 in Fig. 4, thus 30 effectively clamping the end connector to the elastic ribbon so as to withstand hard pull. The prongs 15 are then bent transversely, preferably as shown in Fig. 4, in position for attachment to the hat sweat band. To secure the elastic ribbon, equipped with an end connector at each end as described, to the sweat band, the prongs 15 are thrust through the sweat band 13 and the prongs bent toward each other as shown in Fig. 5 so that they will lie flat. The prongs are 35 preferably pushed in from the outside of the sweat band, the sharp prongs being flat between the inner side of the sweat band and the inner side of the hat and concealed from view. The elastic ribbon may be replaced or removed by merely 40 opening the sweat band and bending up the prongs.

It can thus be readily seen that the end connector of the present invention is easy and economical to manufacture since it can readily be 50 stamped from sheet stock, is simple in construction inasmuch as it can be readily attached to an elastic ribbon without the necessity of tools, and can be easily attached to a hat sweat band without special tools and instruments. The in- 55

vention may be applied to other uses, and the end connector may be applied to tapes and straps in general.

While I have described a specific constructional embodiment of my invention, any desired changes in the materials used for the parts, in their relative proportions, and in the assembly to the elastic ribbon, may be made to suit the requirements for different elastic ribbons with-
10 out departing from the spirit and the scope of the invention as defined in the appended claim.

I claim:

An end connector for a tape comprising a base plate folded longitudinally to provide a lower plate portion and an upper plate portion of simi-
15

lar contour and adapted to clamp over a tape end inserted therebetween, one plate portion having triangular lock prongs of substantial length on the side edge portion thereof and extending transversely away therefrom, whereby said lock prongs may be locked to a support to secure the tape thereto, one plate portion having triangular engaging teeth on the longitudinal edge thereof extending towards the other plate portion, said other plate portion being of 10 greater width and having its longitudinal edge portion extending towards the engaging teeth to provide a guard therefor when in clamped position.

JOHN W. W. HOLDEN. 15
